UNITED STATES PATENT OFFICE.

EDWARD D. YATES, OF FRANKLIN, PENNSYLVANIA.

OIL-WELL PUMPING-RIG.

SPECIFICATION forming part of Letters Patent No. 635,630, dated October 24, 1899.

Application filed July 25, 1899. Serial No. 725,092. (No model.)

To all whom it may concern:

Be it known that I, EDWARD D. YATES, residing at Franklin, in the county of Venango and State of Pennsylvania, have invented certain new and useful Improvements in Oil-Well Pumping-Rigs, of which the following is a specification.

This invention relates to improvements in well pumping-rigs, and more particularly to that portion of the rig where the pump-actuated rods are attached to the power-shaft; and it primarily has for its purpose the simplifying of the adjustment and connection of the pump-actuated rods to the power-shaft; the adding of strength to said parts where most desired, and decreasing the friction to the minimum.

In its more specific nature this invention seeks to improve the construction of the rig mechanism disclosed in my Patent No. 593,826, dated November 16, 1897. In my aforesaid patent the power-shaft has its crank portions made non-circular to receive a sectional sleeve having two or more vertical exterior bearings, a horizontal bearing intermediate the vertical bearing portions, and upper and lower horizontal bearings, the sectional actuating-disk, also forming a part of the said patented construction, which is mounted upon the horizontal and vertical bearings of the shaft-sleeve, the said disk having a series of alternately radially disposed dovetailed sockets, a bolt-aperture in each socket, and a bolt-aperture at a point intermediate the inner end of each pair of sockets, said sockets being arranged to receive the dovetailed sockets of the pump-rods that are made secure to the disk by bolts passing through the rods and the apertures in the said disk.

While I have found my patented construction aforesaid entirely practical, yet experience has demonstrated the results as not being all that is desired, and my present improvements are intended to add greatly to the value of my former mechanism and render the operation of my complete rig the more effective, economical, and convenient.

With these objects in view my present invention comprehends generally sectional sleeves adapted to engage with the non-circular portions of the crank-shaft and each sleeve formed with upper and lower horizontal bear-

ings and clear of intermediate bearings, and sectional bearing-boxes adapted to fit upon the said sleeves, each box engaging with and being mounted on its corresponding sleeve, with its upper and lower ends to engage with the upper and lower horizontal sleeve-bearings, said bearing-boxes being of two like-constructed parts having a plurality of segmental radially-extended flanges disposed in different horizontal planes, the several flanges of each section overlapping each other, whereby to provide more space for securing the rods than can be obtained with an ordinary single disk member and leaving the flanges in a more useful condition, as well as making the entire box of great strength and durability.

In its subordinate features this invention consists in certain details of construction and peculiar combination of parts, all of which will be hereinafter fully described, and further pointed out in the appended claims, reference being had to the accompanying drawings, in which—

Figure 1 is a perspective view of my improved pumping-rig. Fig. 2 is a horizontal section on the line 2 2 of Fig. 3. Fig. 3 is a vertical section on the line 3 3 of Fig. 2. Fig. 4 is a perspective view of a bearing-box and sleeve detached. Fig. 5 is a detail view of the two sections that form the bearing-boxes disconnected from each other, and Fig. 6 is a side elevation of one of the crank-axle sleeve members.

In the accompanying drawings, 1 indicates the rig frame or support, which may be of any approved construction; but on the score of economy of manufacture, strength, and convenience in setting up I prefer to construct said frame 1 as shown in the accompanying drawings. The power-shaft in the construction shown has open crank portions 2^a 2^b, projected approximately in diagrammatically opposite directions, and in the said drawings one of the crank portions 2^b is shown disposed above the cross-head 1^a of the supporting-frame 1, while the other crank portion 2^a is located between the master or drive gear 3 and the cross-head 1^a, as clearly shown in Fig. 1, by reference to which it will also be seen that the gear 3 meshes with a bevel-gear 4^a on the power-shaft 4, having the drive-pulley 4^b, which is driven in any well-known manner.

The crank portions of the shaft in the present form are made non-circular, as shown, and upon each of the said crank portions is mounted a sleeve 7, formed of two sections having 5 internal bearing-faces to snugly fit the shaft and held from turning thereon, and each section 7 has on the upper and lower ends a semicircular flange 7^x, the flanges of the two sections when joined forming the upper and 10 lower horizontal bearing members for a purpose presently explained.

So far as described, it will be seen that each crank-shaft portion has a supplemental sectional bearing that can be readily applied 15 thereto or removed therefrom, as desired.

Referring now more particularly to Figs. 2 to 5, the construction of one of the bearing-boxes or pump-rod-attaching hubs will be readily seen, the peculiar construction of 20 which, *per se*, and its combination with the crank-axle-bearing sleeve and crank-axle forms the essential feature of my present invention.

The hub or box bearing (indicated by 8) consists of two half-sections 8^a 8^a, constructed alike and when joined the two sections form a hub adapted to snugly engage and rotate upon the sleeve 7, said hub being of a height corresponding to the length of the flat bearing-surfaces of the sleeve 7, and to minimize the friction the upper face of the lower horizontal bearing-flange of the sleeve 7 has a ball-race 7^x, in which are held the bearing-balls 9, the upper sides of which engage the 30 races 8^c in the under side of the hub 8, as clearly shown in Fig. 3, and while I have not so illustrated the same it is obvious a ball-bearing may be provided for the upper face of the said hub 8. Each hub-section 8^a has a semi-circular bearing-groove whereby to provide 35 for a free rotation upon the crank-axle sleeve when the several parts are properly adjusted, as best illustrated in Fig. 1. On the outer face of each hub-section 8^a is integrally formed 40 a plurality of annular segmental flanges, two being shown and designated, those on one section by *a b* and those on the other section by *a' b'*, and each section 8^a has laterally-projected vertically-extending flanges 8^d, that 45 receive the fastener-bolts 10, which secure the two sections together. The upper flange *a* or *a'* of each section begins at the bolt-flange 8^d at one side of the said section and extends annularly three-fourths, more or less, 50 55 the distance between the end flanges 8^d, while the lower flange *b* or *b'* begins at the opposite flange 8^d (meaning the one adjacent the end of the flange *a* or *a'*) and extends a like distance annularly around the section in a direction reverse to that in which the flange *a* or *a'* extends.

While I have shown the flanges *a a'* and *b b'* as extending, say, three-fourths around the hub, such exact length is not absolutely essential, as the flanges may be of a less length; 60 65 but I prefer to make them sufficiently long,

so that their inner ends will pass each other or lap, as shown in the drawings. By forming the hub with the radial flanges, as described, it is manifest when the two hub-sections are joined the complete hub will have two upper segmental horizontal flanges projected in diametrically opposite directions and two lower horizontal flanges also projected in a diametrically opposite direction to each other, but 70 alternately to that of the upper flange. This gives the hub, as it were, a continuous annular flange, to which the ends of the pump-rods 12 may be readily secured, and by reason of the flanges overlapping, or, in other words, extending partially over each other, additional rod-securing surfaces are provided not obtainable in the disk connection—such, for example, as in my other patent before referred to. Each hub-flange has a series of 80 85 perforations 13 for the pivot-bolts that secure the bifurcated or strap ends of the rods 12, as shown.

So far as described it will be readily apparent that by having the flanges overlapping 90 in the center of the hub—that is, at a point at right angles to the meeting edges of the two sections—serves to spread the extra strength that they are intended to give the hub, and yet keep the flanges close enough together, so 95 that both of the said flanges can be used at a point where they overlap whenever a very heavy line of rods are to be connected, a contingency constantly made necessary where there are many wells and heavy lines are run 100 out to pull wheels, thus providing a means for attaching the rods to the power-shaft, in itself of great strength and capable of making fast many and very heavy pump-lines.

By providing a hub having flanges, as described and shown, places the extra weight at the places where all of the strain comes, as well as adding considerable more space for rod connections than a single flange would give it, at the same time giving double 105 strength to the face of the hub and also saving a considerable weight by the flanges not extending around the said hub. Again, by having the two sets of flanges in different horizontal planes places the rod-attaching 110 portions in a more useful position, for the reason that the pull strain is thereby the more equalized, as the uphill well-rods can be secured to the upper flanges and the downhill well-rods to the lower flanges, thereby distributing the strain on the hub in such a manner that it will work as easily upon the sleeve 115 7 as if the pull strain from all directions were in a like horizontal plane.

From the foregoing description, taken in 120 125 connection with the accompanying drawings, it is thought the complete operation and advantages of my present invention will be understood by those skilled in the art to which it appertains.

The rods can be more conveniently and 130 quickly attached than in the manner shown

in my other patent, a greater number can be connected to each rig, and more satisfactory results obtained with the simplified construction than is possible by the means shown in 5 my aforesaid other patent.

Having thus described my invention, what I claim, and desire to secure by Letters Patent, is—

1. In a pumping-rig of the character described; the combination with the operating crank-shaft; of the hub or bearing-box rotatable on the said shaft, said hub having integral therewith a plurality of segmental horizontal flanges disposed in different planes, 15 the adjacent or inner edges of the different flanges overlapping each other for the purposes described.

2. In a pumping-rig of the character described, the combination with the operating 20 crank-shaft and a divided hub fixedly held thereon, said hub having upper and lower bearings; of a divided hub or bearing-box mounted upon the said hub between its upper and lower bearings, each hub-section having 25 integral therewith a plurality of segmental external flanges, each flange being less than a semicircle, the flanges being in different horizontal planes, and having their inner ends overlapping each other, and means for securing 30 the pump-rods to the said flanges.

3. The combination with the crank-shaft and the divided sleeve fixedly mounted thereon, said sleeve having a horizontal bearing formed with a ball-race and the bearing-balls 35 held in said races; of a sectional hub rotatably mounted on the sleeve and having a ball-race to engage the bearing-balls carried on the said sleeve, the hub-sections each having integral therewith a plurality of segmental 40 radial flanges disposed in different horizontal planes, the coincident flanges of the two sections being in the same plane and the said

flanges being perforated for the rod-securing bolts, substantially as shown and described.

4. In a pumping-rig of the character described, 45 the combination with the crank-shaft; of a hub or bearing-box rotatably held thereon, said hub having two correspondingly-formed sections, each section having integral therewith a pair of radially-extended peripheral flanges disposed in different horizontal planes, the upper one beginning at one edge of the section and extending partially around the same, the lower one beginning at the opposite edge of the section and extending 50 around said section to a point beyond the inner end of the upper flange, whereby the inner edges of the two flanges will lap each other, substantially as shown and for the purposes described. 55

5. In an oil-well pumping-rig, the combination with the supporting-frame; the crank-shaft journaled thereon; means for operating such shaft, said shaft having its crank portion made non-circular; a sectional sleeve 65 fixedly held on such crank portion, said sleeve having a circular external bearing and upper and lower horizontal bearings; a sectional rod-actuating hub mounted to rotate upon the crank-axle sleeve, said hub having integral 70 therewith a series of alternately radially projecting flanges arranged in different horizontal planes, said flanges having bolt-apertures whereby to secure the inner ends of the bolt and rods thereto, the upper flanges of the 75 said actuating-hub projecting across the hub sufficiently to lap the flanges below them, all being arranged substantially as shown and described.
